BRUSH SPRING RETRACTOR

Filed March 30, 1949

UNITED STATES PATENT OFFICE

2,507,981

BRUSH SPRING RETRCTOR

Herbert A. Krause, Brookfield, Ill., assignor to
 General Motors Corporation, Detroit, Mich., a
 corporation of Delaware

Application March 30, 1949, Serial No. 84,427

4 Claims. (Cl. 171—324)

1

The present invention relates to retracting tools and more particularly to a retracting tool for the brush fingers of dynamoelectric machines.

The principal object of the invention is to provide a compact retracting tool which is readily engageable with the various brush fingers of the brush holders located in the confined space adjacent the commutator or slip rings in dynamoelectric machines for readily retracting these fingers.

Another object is to provide releasable tool latching means engageable with a portion of the brush holder to retain the tool and brush finger engageable thereby in the retracted position in order to readily and safely replace the brushes.

The novel features of the tool by which these objects are accomplished are clearly described in the following detailed description and are illustrated in the accompanying drawings.

Figure 1 of the drawings is a side elevational view of the retracting tool shown engaged with a brush finger in the normal operative position.

Figure 2 is a view similar to Figure 1 with the tool and brush finger in the retracted position and retained in this position upon engagement of the latching means of the tool with the brush holder.

Figure 3 is an enlarged perspective view of the tool showing the specific details of the tool assembly.

As best shown in Figure 3 the brush retracting tool comprises a main lever 1 having a handle portion 3 at the outer end and a bifurcated inner end fulcrum portion. The two legs 5—7 of the bifurcated fulcrum portion are downwardly curved at the extremities thereof. Brush finger engaging means are provided on the lever 1 comprising a depending U-shaped stirrup 9 secured to the lever intermediate the ends. The lever 1 is shown provided with an upstanding side portion 11 intermediate the ends and a latching lever 13 is pivoted intermediate its ends by means of a pivot pin 15 to this upstanding portion 11 of the main lever 1 for angular movement relative thereto. The latching lever 13 is provided with an outer end handle portion 17 located above the handle portion 3 of the main lever 1 and a downwardly extending hooked portion 19 is provided on the inner end of the latching lever located above the leg 5 of the bifurcated inner end fulcrum portion of the main lever 1. A leaf spring 21 is secured at one end to the upper face and at one side of the main lever handle portion 3 and the other end of the spring 21 extends upwardly and engages the underside of the latching

2

lever handle portion 17 adjacent the pivot pin 15 to oppose angular movement of the latching lever handle portion angularly into engagement with the main lever handle portion 3 and normally retain the portion of the latching lever adjacent the hooked inner end portion 19 in contact with the leg 5 of the main lever fulcrum portion.

The above described brush finger retracting tool is shown in Figure 1 with the depending stirrup 9 of the main lever engaged with a hooked portion 23 of a brush finger 25 and the curved legs 5—7 of the bifurcated fulcrum positioned along opposite sides of a spring anchor lever 27 of a brush holder frame 29 of well known type secured in conventional manner to the stator of a dynamoelectric machine, not shown, adjacent the peripheral surface 31 of the commutator or slip rings, shown in dotted line, of the rotor of the machine. The spring anchor lever 27 is provided with a hub portion 33 pivoted on an insulating bushing 34 on a pin 35 supported at the ends on the brush holder frame 29. The anchor lever may be positioned angularly with respect to the bushing and held in different angular positions thereon by means of a key 36 engageable in one of a plurality of slots 37 in the hub portion 33 of the anchor lever. The key 36 is releasably secured by a machine screw 38 to the brush holder frame 29. The brush finger 25 is also pivoted on the bushing 34 by means of side bearing portions 39 spaced axially either side of the anchor lever hub portion. A brush finger spring, generally indicated at 41 having the opposite ends 43 shown hooked over the finger side bearing portions 39, adjacent helical portions 45 around the portions of the bushing 34 and an upstanding central loop portion 47 engageable with the opposite ends of a pin 49 secured in an opening in the end of the anchor lever 27 serves to urge the outer end of the finger 25 into contact with the outer end of a brush 51 slidable in a slot 53 in the brush holder frame and thereby hold the inner end of the brush in firm contact with the peripheral surface 31 of the commutator or slip ring.

The main lever 1 of the brush finger retracting tool is shown in Figure 1 in position to retract the brush finger 25. The curved legs 5—7 of the bifurcated fulcrum portion of the main lever are shown engaged with the helical portions 45 of the spring and the main lever stirrup 9 is in engagement with a hooked portion 23 of the brush finger. It will be evident that clockwise movement of the main lever 1 from this engaged

position moves the brush finger 25 clockwise away from the brush 51 against the action of the finger spring 41 and the hooked end 19 of the pivoted latching lever is positioned by the leaf spring 21 to engage the key 36 and hook over the outer end surface thereof, as shown in Figure 2, when the brush finger is fully retracted to hold the tool and finger in the retracted position. The leaf spring 21 serves in the same manner when the retracting tool is inverted and engaged with the brush finger in another brush holder frame positioned adjacent the diametrically opposite or lower side of the commutator or slip ring surface 31.

The construction of the above described retracting tool enables brush fingers located in the limited space available in dynamoelectric machines to be easily retracted and held in this position whereby the brushes may be safely replaced.

I claim:

1. In a retracting tool for a spring biased brush finger pivoted in a brush holder of a dynamoelectric machine, a main lever, a latching lever pivoted thereon, said main lever having brush finger engaging means and a fulcrum portion engageable with a portion of the brush holder, said latching lever having a hooked end portion engageable with another portion of the brush holder when the finger is retracted by the main lever.
2. In a retracting tool for a spring biased brush finger pivoted in a brush holder of a dynamoelectric machine, a main lever having brush finger engaging means and a fulcrum portion contactable and movable with respect to the brush holder, a latching lever pivoted on the

main lever and having a latch portion engageable with another portion of the brush holder when the main lever is moved relative to the brush holder to retract the brush finger and a spring normally urging the latching lever.

3. In a retracting tool for a spring biased brush finger pivoted in a dynamoelectric machine brush holder, a main lever having a handle portion on the outer end, a fulcrum portion on the inner end adapted to engage a portion of the brush holder and means intermediate the ends engageable with the brush finger, a latching lever pivoted intermediate the ends on the main lever, a hook-shaped inner end portion adapted to releasably engage a portion of the brush holder when the finger is retracted, and a spring engageable with the handle portions of both levers normally positioning the hook-shaped inner end portion of the latching lever for engagement with the brush holder.

4. In a retracting tool for a spring biased brush finger in a dynamoelectric machine brush holder, a main lever having brush finger engaging means intermediate the ends, a bifurcated fulcrum inner end portion engageable with the brush holder either side of the finger and an outer end handle portion, a latching lever pivoted intermediate the ends to the main lever, a hook-shaped inner end portion and an outer end handle portion and spring means for urging the handle portions of the main and latching levers apart and positioning the hook-shaped inner end portion of the latching lever into releasable latching engagement with the brush holder upon retraction of the finger when engaged by the main lever.
